UNITED STATES PATENT OFFICE.

ANDREW J. NICHOLS, OF OZARK, ARKANSAS.

DRY-GOODS EXHIBITOR.

SPECIFICATION forming part of Letters Patent No. 369,464, dated September 6, 1887.

Application filed April 13, 1887. Serial No. 234,605. (No model.)

To all whom it may concern:

Be it known that I, ANDREW J. NICHOLS, of Ozark, in the county of Franklin and State of Arkansas, have invented a new and Improved 5 Dry-Goods Exhibitor, of which the following is a full, clear, and exact description.

My invention has for its object to provide a simple and convenient device for holding oil-cloth, dress-goods, and other fabrics, so that 10 they will be protected from injury, while a sample of each may be displayed.

The invention consists in certain novel features of construction and combinations of parts, as hereinafter fully described, and defined by 15 the claims.

Reference is to be had to the accompanying drawings, forming a part of this specification, in which similar letters of reference indicate corresponding parts in all the figures.

20 Figure 1 is a vertical section of my improved dry-goods exhibitor. Fig. 2 is a side elevation of the same. Fig. 3 is a front elevation. Fig. 4 is a detail sectional view showing one of the carrying-rollers and its bearings. Figs. 5, 6, 25 and 7 are detail views of the various bearings used for the carrier-rollers.

The case of the exhibitor is formed of the sides A A', the top B, the back C, and the ornamental front piece, D, the sides being connected at the bottom by a cross-bar, E.

In the sides A A', near the front edges of the same, are journaled a vertical series of guide-rollers, F, at equal distances apart, and directly above the lower roller F is arranged a 35 pressure-roller, G, which is held yieldingly against the same by means of springs H (only one shown) acting on the bearings of said roller G.

At the rear and in the plane of each guide- 40 roller F is arranged a square carrier-roller, K, on which the goods are rolled, the carrier-rollers being arranged alternately in vertical series near the front and the back of the case, respectively, so that the goods on adjacent 45 rollers will not interfere with each other.

Between the several members of the rear 50 series of carrier-rollers K and the corresponding front guide-rollers F are journaled a series of secondary guide-rollers, I, over which the goods pass from the said carrier-rollers to the front guide-rollers F so as to be held out

of the way of the goods on the front series of carrier-rollers when the same are full.

The carrier-rollers K are journaled to the side A' of the case in bearings L, held therein, 55 and to the side A in bearings M, and are provided at these latter ends with squared extensions N, projecting into holes N', formed through the side A of the case, the bearings M being sectional, as in Fig. 6, to permit the insertion of the squared extensions N when putting the parts together.

The squared extensions N are adapted to receive the removable socketed crank-handle P, in order that the carrier-rollers K may be 60 turned for winding the goods thereon.

The goods on the several carrier-rollers can be fully displayed by letting their free ends hang over their respective guide-rollers F, as indicated in dotted lines in Fig. 1, and can be 70 readily drawn out over said rollers for cutting, measuring, &c.

In rewinding the goods on their rollers K, they are passed between the lower guide-roller F and the pressure-roller G, to which they are 75 guided between brackets Q, projecting at the bottom from each side A A' of the case and parallel therewith, and are thus wound smoothly and evenly on the carrier-rollers.

A downwardly-swinging door, C', is arranged 80 in and extending across the back C of the case, by which easy access is gained to the interior of the case.

When it is desired to remove all the goods from any of the carrier-rollers K, such goods 85 are wound directly therefrom upon a secondary carrier-roller, K', arranged across the back of the case, as indicated in dotted lines in Fig. 1.

The roller K' is journaled in slotted bearings Q', fixed to the sides of the case, at the 90 rear edges of the same, said slots leading at an upward incline to said rear edges at the sides of the opening in the back, so that when the door closing said opening is swung down and the goods wound on the secondary carrier-roller 95 the same may be removed or replaced at will.

Having thus fully described my invention, what I claim as new, and desire to secure by Letters Patent, is—

1. An exhibitor comprising a case, the guide- 100 rollers F, arranged at the front of the case, the carrier-rollers K, journaled in the case in the

plane of the guide-rollers and arranged alternately in vertical rows near the front and back of the case, and the secondary guide-rollers I, between the rows of guide-rollers, substantially as herein shown and described.

2. In an exhibitor, the combination of a case, a series of guide-rollers in front of the same, carrier-rollers in rear of the guide-rollers, and a yielding pressure-roller, G, arranged above the lower guide-roller, substantially as herein shown and described, whereby provision is made for winding the goods on the carrier-rollers smoothly and evenly, as set forth.

3. In an exhibitor, the combination, with the case having an opening in its back and a series of guide and carrier rollers journaled in the case, of a secondary carrier-roller, K', journaled in the rear of the case, substantially as herein shown and described.

4. In an exhibitor, the combination, with the case having an opening extending across its back and the series of guide and carrier rollers in the case, of a secondary carrier-roller journaled across the back of the case, at the opening thereon, and the bearings of said secondary carrier-roller having inclined slots opening at the rear edges of the sides of the case, substantially as shown and described.

5. In an exhibitor, the combination, with the case and the guide and carrier rollers journaled transversely therein, of parallel guide-brackets projecting from the front edges of the sides of the case, substantially as shown and described.

ANDREW J. NICHOLS.
